UNITED STATES PATENT OFFICE.

IRA READ PUTNAM, OF LANCASTER, KANSAS.

LEVER TRANSMITTING MECHANISM FOR PUMPS.

1,286,768.

Specification of Letters Patent.

Patented Dec. 3, 1918.

Application filed November 2, 1917. Serial No. 199,895.

To all whom it may concern:

Be it known that I, IRA READ PUTNAM, a citizen of the United States of America, residing at Lancaster, in the county of Atchison and State of Kansas, have invented certain new and useful Improvements in Lever Transmitting Mechanism for Pumps, of which the following is a specification, reference being had therein to the accompanying drawing.

This invention relates to a lever transmitting mechanism for pumps and has for its object the production of a simple and efficient lever transmitting mechanism whereby the discharge spout of the pump may be located at a distance from the well.

Another object of this invention is the production of a simple and efficient lever means for efficiently operating the plunger 20 of the pump for forcing water or other liquid down through the extension connected directly with the pipes extending down into the well.

With these and other objects in view this invention consists of certain novel constructions, combinations and arrangements of parts as will be hereinafter fully described and claimed.

In the drawings:

Figure 1 is a side elevation of the pump mechanism, the base being shown partly in section.

Fig. 2 is a top plan view of the pump mechanism.

Fig. 3 is a section taken on line 3-3 of Fig. 1.

Fig. 4 is a section taken on line 4-4 of Fig. 1.

Fig. 5 is a section taken on line 5-5 of Fig. 1.

Fig. 6 is a section taken on line 6-6 of Fig. 1.

Fig. 7 is a section taken on line 7-7 of Fig. 2.

Fig. 8 is a detail perspective view of one of the pump actuating links.

Fig. 9 is a detail perspective of one of the bell crank levers used in connection with the pump operating mechanism.

Fig. 10 is a detail perspective of the inner end of the intermediate operating link 1.

By referring to the drawing it will be seen that 1 designates the objects which may be of any suitable or desired construction but is preferably formed of concrete or other suitable material. The base 1 is provided

with a channel 2 formed therein through which channel 2 extends the pump extension pipe 3 as shown clearly in Figs. 1 and 4. This pump extension pipe 3 is suspended upon a pair of hanger brackets 4 which hanger brackets 4 are riveted, bolted or otherwise secured to the metal cover plate 5 carried by the objects 1. This cover plate 5 is held securely in engagement with the base 1 by means of suitable bolts 6. The cover plate 5 is made up of a plurality of sections and the sections of this cover plate 5 are connected by means of the connecting plates 7 which plates are firmly bolted to the cover plate 5 by means of suitable bolts 8.

The inner end of the pump extension pipe 3 is connected to a T joint 9 which T joint 9 is carried by the upper end of the pump pipe or pump cylinder 10. The usual pump rod 11 extends down through the pipe 10 and carries a head 12 which head is engaged by means of the connecting links 13 and these connecting links 13 are in turn pivotally connected to the primary link rod 14 shown clearly in Figs. 1, 5 and 8. The primary link arm 14 is pivotally mounted upon a standard or bracket 15 by means of a suitable pivot bolt 16 and this bracket 15 comprises a pair of similarly constructed sections which are secured to the cover plate 5 by means of securing bolts 17 shown clearly in Fig. 2 of the drawings.

An intermediate link arm 18 is pivotally mounted upon the supporting brackets 19 which are in turn connected to the cover plate 5 and the outer end of this link arm 18 engages a plurality of connecting links 20 which connecting links 20 also engage the inner end of the primary link arm 14. The inner end of this intermediate link arm 18 carries a plurality of vertically extending connecting links 21 which vertically extending links 21 engage the projecting finger 22 of the bell crank lever 23. This bell crank lever 23 is provided with a pair of oppositely extending arms 24 which oppositely extending arms 24 are engaged by means of the crossed connecting rods 25 shown clearly in Fig. 1 of the drawings. The opposite ends of these crossed rods 25 are also connected to the laterally extending ends 26 of the bell crank lever 27 and the forwardly extending finger 28 of the bell crank lever 27 is connected to a vertically extending rod 29 as shown clearly in Fig. 1. The bell crank lever 27 is pivotally mounted upon a stand-

ard or bracket 30 of suitable construction. The rod 29 carries a head 31 at its lower end and a head 32 at its upper end the rod 29 being threaded into the heads 31 and 32 as shown clearly in Fig. 6. The upper head 32 is pivotally connected to a pump handle 33 by means of a pivot bolt 34. And this pump handle 33 is pivotally mounted upon a standard 35 carried by the pump discharge 10 spout 36. This pump discharge spout 36 communicates with the extension pipe 3.

It should be understood that when it is desired to pump water out through the spout 36, the pump handle 33 is operated thereby 15 reciprocating the rod 29 and rocking the bell crank levers 27 and 23. This of course will rock the intermediate link arm 18 and also the primary link arm 14 thereby reciprocating the pump rod or plunger rod 11 for 20 drawing the water or liquid up through the pipe 10 and discharge the same out through the T joint 9, through the pipe 3, and up through the discharge spout 36. It should be understood that the pipe 3 may be placed 25 below or above ground to suit the convenience of the operator and it should be further understood that the pump may be placed in any desired position with respect to the well such for instance for the purpose of conveying 30 water from a well located outside of the house or barn used into a house or barn. By means of the present invention it will be seen that the location of the well is immaterial for the reason that the water or liquid 35 raised from the well may be conveniently

and efficiently discharged from the well through the medium of the operating means at any suitable or desired distance from the well.

What is claimed is:

1. A mechanism of the class described comprising a pump rod, a primary link arm coöoperating with said pump rod for reciprocating the same, an intermediate link arm coöoperating with said primary link arm for actuating the same, a plurality of standards, bell crank levers carried by said standards, one of said bell crank levers coöperating with said intermediate link arms, crossed rods connecting the respective bell crank 45 levers, a pump handle and means connecting the other bell crank lever to said pump handle. 50

2. An operating mechanism of the class described comprising a base, an extending pipe mounted thereon, a covered plate connected to said base, said covered plate formed by a plurality of sections, transversely extending plates over-lapping the abutting ends of said sections, standards carried by said covered plate, lever mechanism pivotally mounted upon said standards, a pump handle for operating said lever mechanism, means connecting said handle to said lever mechanism, and a pump rod actuated 55 by and connected to said lever mechanism. 60

In testimony whereof I hereunto affix my signature.

IRA READ PUTNAM.
